UNITED STATES PATENT OFFICE.

JOHN SHEARMAN, OF BROOKLINE, MASSACHUSETTS.

WRENCH.

1,413,622.

Specification of Letters Patent. Patented Apr. 25, 1922.

Application filed May 13, 1921. Serial No. 469,254.

To all whom it may concern:

Be it known that I, JOHN SHEARMAN, a citizen of the United States, residing at Brookline, in the county of Norfolk and 5 State of Massachusetts, have invented new and useful Improvements in Wrenches, of which the following is a specification.

This invention relates to an improvement in pipe wrenches.

- 10 The object of the invention is to provide a pipe wrench of simple and durable construction which may be easily and quickly adjusted to fit pipes of various diameters or other objects of various sizes.
- 15 Another object of the invention is to provide a device of the character disclosed having a fixed jaw provided with a plurality of sets of permanently located gripping teeth and a movable jaw which may co-operate 20 with each of the sets of gripping teeth of the fixed jaw to engage and grip the objects desired.

The invention consists in the combination and arrangement of parts set forth in the 25 following specification and particularly pointed out in the claims thereof.

Referring to the drawings:

Figure 1 represents a side elevation of a wrench embodying my invention.

30 Fig. 2 represents a side elevation partly in section illustrating my improved wrench applied to a pipe.

Fig. 3 is a view similar to Fig. 2 illustrating another manner in which my improved 35 wrench may be applied to a pipe.

Fig. 4 is a horizontal section taken on the line 4—4 of Fig. 1.

Fig. 5 is a vertical section taken on the line 5—5 of Fig. 1.

40 Like numerals refer to like parts throughout the several views of the drawings.

In the drawings, 7 represents a shank, one end of which is secured in any desired manner within a suitable handle 8, while the 45 other end thereof terminates in an enlarged portion constituting a fixed jaw 9. The fixed jaw 9 is formed to provide two sets of suitably formed gripping teeth 10 and 11, the teeth 10 being located upon the outer 50 extremity of said fixed jaw 9 while the teeth 11 are located upon the front edge of said jaw. Extending transversely through the fixed jaw 9 is a slot 12 in which is located a pin 13 which constitutes a pivot for a yoke 55 14. The yoke 14 embodies therein plates 15 and 16 arranged parallel to each other

upon opposite sides of the shank 7 and jaw 9, said plates being held in correct spaced relation to each other by pins 17 and 18 and the pivotal pin 13, the opposite ends of 60 each of said pins being preferably riveted to said plates. The yoke 14 is furthermore slidable upon the shank 7 within the limits permitted by the length of the slot 12.

Slidably mounted within the yoke 14 between the plates 15 and 16 is a member 19, one end of which is bent to form a jaw 20 constituting a movable jaw and provided with suitably formed gripping teeth 21 which are opposed to the teeth of the fixed 70 jaw 9. The front and rear edges of the slidable member 19 are provided with sets of teeth 22 and 23 respectively each of which are preferably formed similar to rack teeth. The teeth 22 are provided to engage and co-operate with the teeth 10 of the fixed jaw 9 when the device is used as illustrated in Fig. 3, while the teeth 23 also formed similar to the teeth 22 are adapted to engage and co-operate with the pins 17 and 18 to prevent 80 a longitudinal movement of the slidable member 19 between the plates 15 and 16 of the yoke 14 when said slidable member has been adjusted to a suitable position for the gripping jaws 9 and 20 to operatively engage 85 a pipe A.

A pin 24 located adjacent to the lower end of the slidable member 19 and extending therethrough is adapted to engage the under edge of the plates 15 and 16 of the yoke 14 90 to limit the movement of said slidable member within said yoke and also to prevent said slidable member from becoming removed therefrom. It is evident that the teeth 10, 22 and 23 may be formed in any suitable 95 manner without departing from the spirit of this invention.

In the operation of the wrench the movable member 19 may be adjusted, as illustrated in Fig. 2, to correctly position the 100 jaw 20 for the teeth 21 thereof to co-operate with the teeth 10 of the fixed jaw 9 to engage the pipe A, at which time the teeth 23 of said movable member will engage the pin 17 which will thereafter prevent said movable member from moving longitudinally within the yoke 14. If, on the other hand, however, it is found more convenient to operate the wrench as illustrated in Fig. 3, the yoke 14 is slid longitudinally of the 110 shank 7 within the limits of the slot 12 and then tipped upon the pivot 13 to the position

22
 illustrated in said Fig. 3. The movable member 19 is then adjusted within the yoke 14 to a position where the teeth 21 will co-operate with the teeth 11 of the fixed jaw 5 to engage the pipe A. At such times the pin 17 will prevent the movable member 19 from moving longitudinally within the yoke 14 and in certain cases, the position of the movable member 19 will be such that 10 the pin 18 will co-operate with the pin 17 in preventing this longitudinal movement of the movable member 19.

It will be noted that when the various parts are positioned as illustrated in Fig. 3 15 and the shank 7 is rocked in the direction of the arrow a, the pin 17 will act as a fulcrum for the movable member 19 and the gripping teeth 10 will co-operate with the teeth 22 to force the movable member 19 toward 20 the right in said Fig. 3 and thereby cause the teeth 11 and 21 of the jaws 9 and 20 respectively to very tightly grip the pipe A.

I claim:

1. A wrench having, in combination, a 25 shank provided with a fixed jaw having a plurality of toothed gripping edges, a yoke pivotally mounted upon said shank and a member slidably mounted within said yoke and provided with a toothed gripping edge 30 adapted to co-operate with each of the toothed edges of said fixed jaw to grip an object therebetween, said slidably member also embodying therein means adapted to engage a portion of said yoke and thereby 35 prevent a longitudinal movement of said slidably member therein.

2. A wrench having, in combination, a shank provided with a fixed jaw having a 40 plurality of toothed gripping edges, a yoke pivotally and slidably mounted upon said shank and a member slidably mounted within said yoke and provided with a toothed gripping edge adapted to co-operate with each of the toothed edges of said fixed jaw 45 to grip an object therebetween, said slidably member also being provided with teeth adapted to engage a portion of said yoke and thereby prevent a longitudinal movement of said slidably member therein.

50 3. A wrench having, in combination, a shank provided with a fixed jaw having a plurality of toothed gripping edges, a yoke pivotally and slidably mounted upon said shank and a member slidably mounted 55 within said yoke and provided with a toothed gripping edge adapted to co-operate with each of the toothed edges of said fixed jaw to grip an object therebetween, said slidably member also embodying therein sets 60 of teeth located upon the front and rear edges thereof, one of said sets of teeth being adapted to engage a portion of said yoke to prevent a longitudinal movement of said slidably member therein and the other set 65 of teeth being adapted to interlock with the

teeth of one of the gripping edges of the fixed jaw.

4. A wrench having, in combination, a shank embodying therein a fixed jaw having a plurality of toothed gripping edges 70 and provided with a slot extending therethrough, a yoke pivoted within said slot and embodying therein a pair of parallel plates and a plurality of pins, the opposite ends of which are rigidly secured to said plates 75 and a member slidably mounted between said plates and provided with a toothed portion constituting a movable jaw opposed to said fixed jaw, said slidably member also being provided with teeth adapted to engage 80 said pins and thereby prevent a longitudinal movement of said slidably member within said yoke.

5. A wrench having, in combination, a shank embodying therein a fixed jaw having 85 a plurality of toothed gripping edges and provided with a slot extending therethrough, a yoke pivoted within said slot and also slidably upon said shank and embodying therein a pair of parallel plates and a plurality of pins, the opposite ends of which are rigidly secured to said plates and a member slidably mounted between said plates and provided with a toothed portion constituting a movable jaw adapted to co-operate 90 with each of the toothed edges of said fixed jaw to grip an object therebetween, said slidably member also embodying therein sets of teeth located upon the front and rear edges thereof, one of said sets of teeth being adapted to engage said pins to prevent a longitudinal movement of said slidably member between said plates and the other set of teeth being adapted to interlock with 95 one of the gripping edges of said fixed jaw. 100

6. A wrench having, in combination, a shank embodying therein a fixed jaw provided with a plurality of teeth upon the outer edge thereof and a plurality of teeth upon the front edge thereof, a yoke pivotally 110 and slidably mounted upon said shank and a member slidably mounted within said yoke and provided with a toothed gripping edge adapted to co-operate with each of the toothed edges of said fixed jaw to grip an object therebetween, said slidably member also embodying therein sets of teeth located upon the front and rear edges thereof, one of said sets of teeth being adapted to engage a portion of said yoke to prevent a longitudinal 115 movement of said slidably member therein, and the other set of teeth being adapted to interlock with the teeth upon the outer edge of said fixed jaw. 120

7. A wrench having, in combination, a 125 shank embodying therein a fixed jaw provided with a plurality of gear teeth upon the outer edge thereof and a plurality of V-shaped teeth upon the front edge thereof, a yoke pivotally and slidably mounted upon 130

said shank and a member slidably mounted within said yoke and provided with a toothed gripping edge adapted to co-operate with each of the toothed edges of said fixed 5 jaw to grip an object therebetween, said slideable member also embodying therein sets of rack teeth upon the front and rear edges thereof, one of said sets of rack teeth being adapted to engage a portion of said yoke to 10 prevent a longitudinal movement of said slideable member therein, and the other set

of rack teeth being adapted to interlock with the gear teeth upon the outer edge of said fixed jaw.

In testimony whereof I have hereunto set 15 my hand in presence of two subscribing witnesses.

JOHN SHEARMAN.
